UNITED STATES PATENT OFFICE.

WILLIAM G. PRICE, OF NORTH YAKIMA, WASHINGTON.

FRUIT-SIZING MACHINE.

1,288,184.

Specification of Letters Patent. Patented Dec. 17, 1918.

Application filed October 10, 1913. Serial No. 794,476.

To all whom it may concern:

Be it known that I, WILLIAM G. PRICE, a citizen of the United States, and resident of North Yakima, in the county of Yakima and State of Washington, have invented a new and useful Improvement in Fruit-Sizing Machines; and I do hereby declare the following to be a full, clear, and exact description thereof.

10 My invention relates to apparatus for sizing apples or other fruit.

In some of the Western States where apples are grown in large quantities, it is customary to pack these apples in boxes, and 15 while there are many different sizes, only one size is packed in each box, the boxes being all of the same size. The usual method is for the person packing the apples to determine the size by the eye, and as they are 20 packed by hand, the task is an arduous one and at the same time an expensive one, while at the same time there is no assurance that the work will be done accurately so far as the sizing of the apples is 25 concerned.

In my invention I have taken advantage of the fact that the specific gravity of all apples of a variety, as for instance "Jonathans," from one locality, is practically the 30 same, and have devised apparatus by which the sizing is done by weight. Only one variety is run through a machine at one time, and the machine can be adjusted to suit the specific gravity of different varieties of 35 apples, which vary from each other slightly.

To these ends my invention consists, generally stated, in feeding the apples successively into a cup which is moved by a spring of sufficient strength to throw the apples so 40 that they leave the cup as a projectile at an angle of about 45° from the horizontal and by making the cup so light in weight and adjusting the strength of the spring, so it will throw the small sized apple a certain 45 distance and the largest sized apple a correspondingly less distance, the intermediate sizes being thrown varying distances between according to weight, the apples being deposited into bags arranged to receive 50 them, and rolling from the bags into bins from which they are taken to be packed.

In the accompanying drawings, Figure 1 is a longitudinal elevation of my improved apparatus, the cup in its relative position 55 being indicated in dotted lines; Fig. 2 is a plan view; Fig. 3 is a section on the line

3-3 Fig. 1, and Fig. 4 is an enlarged sectional view of the cup.

In the drawings the numeral 2 designates the suitable framework, and near one end 60 of said frame-work is arranged the chute 3, on which the apples to be sized are fed. Mounted in the upright 4 of the frame is the feeding-wheel 5 which consists of two flanges 6 and 7 spaced a suitable distance 65 apart and forming the groove 9 to receive the apples from the chute 3. The feeding-wheel is provided with the pick-up pins 10 which are covered with rubber or other suitable material to prevent the bruising of the 70 apples and said pins are adapted to pick up the apples as they come from the chute 3, and carry them around one by one to be delivered to the chute 11 which projects up into the groove of the feeding-wheel, said 75 chute being supported by the bracket 12 secured to the upright 13 of the frame 2.

The feeding-wheel 5 is provided with the cams 14 on its outer face, said cams being arranged at proper intervals for the purpose more fully hereinafter set forth. The feeding wheel may be driven by hand, by the crank arm 15, or may be driven by any suitable motor. The cup 16 is carried by the arm 17 which may be formed of steel 80 wire of suitable diameter. The wire is doubled and bent to form the loop 18 at one end to receive the cup 16 which may be formed of leather or other suitable material and which is sewed or otherwise secured to the 85 loop 18. The cup is conical in form and is open at the bottom to let dirt or other material fall through. In order to stiffen the leather of the cup and prevent its passing through the rim 18 when the cup is released 90 and the apple discharged, I provide the stiffening plate 19 which may be formed of thin clock-spring steel soldered to the inside of the rim 18 and extending down therefrom and secured to the lower end of the cup in 100 any suitable manner. Furthermore this plate prevents the apple from catching on the rim of the cup when discharged therefrom, as the apple due to centrifugal action will be forced against this metal arm in its 105 discharge from the cup when the cup arm 17 is released, and the leather of the cup at this point is prevented from bulging.

The inner ends of the cup-arm 17 diverge as at 20 where they are connected to the 110 pivot-bearing 21 mounted in the frame. A spring 22 is connected to the cup-arm 17 as

at 23 and said spring is connected to the eye-bolt 24 carried by the frame.

A wire 25 is soldered or otherwise secured to the cup-arm 17, and said wire is connected 5 at its opposite end to the arm 26 on the pivot-bearing 21. A second arm 27 on the pivot-bearing 21 is connected to the link 28 which is connected to the wire 29. The opposite end of the wire 29 is connected to the 10 lever 30 pivoted at 31 in the frame. The upper end of the lever 30 is in the path of the cams 14 and is adapted to be engaged thereby to hold the cup in its lowered or receiving position. In this position the spring 15 22 is extended and just as soon as the cam 14 passes beyond the lever 30 the spring 22 contracts and the cup-arm 17 is raised to the position indicated in dotted lines, Fig. 1, and the apple is discharged from the cup.

20 I provide buffers 32 and 33 which act as stops to control the movement of the cup-arm 17 in the arc through which it moves. The buffer 32 is supported by the upright 13, and said buffer consists of the spools 34 connected to said upright and a piece of raw-hide, or other suitable material, 35 which is passed around the spools and its ends connected by the spring 36. The buffer 33 is of like construction and is carried by the projecting arm 37 of the frame. The cup-arm 17 when released and acted on by the spring 22 strikes the buffer 33, and the impact of the blow is relieved by the yielding action of the buffer. In the same manner when the 30 cup-arm is lowered to receiving position, it comes in contact with the buffer 32 and the force of the impact is likewise relieved.

The bags 38, 39 and 40 are supported by the chains 41 carried by the frame and said 40 bags are connected to said chains by means of the interposed springs 42. The bottom of the bags are inclined, as at 43, and openings 44 are provided through which the apples pass to be discharged into the chutes or bins 45, 46 and 47. Each of these chutes receives apples of a certain size, and the packer stands in position to rake the apples from said chutes and pack them into boxes for shipment.

50 The bags are held at their top and bottom corners by parallel cords 48 which prevent the apple when falling and striking the bag from pushing the bottom of the bag too much out of place, for the apples to roll properly 55 into the bins or chutes. The buffers 49 are carried by the frame and are adapted to cushion the apples as they leave the bags and before they drop into the bins.

I have shown in Figs. 2 and 3 the arrangement 60 of the bags in which the bins are on both sides of the line of bags with every other bag turned in the opposite direction so that half of the apples roll into the bins on one side, and half into bins on the other 65 side. This form of construction permits the

bins to be twice as wide as before, which has points of advantage, as one packer can then take apples from three bins and pack them into three boxes.

As above stated, my invention operates by 70 taking advantage of the difference in weight of the same variety of apples. The smaller sizes of apples vary in weight successively (beginning with the smallest size that is packed) less than $\frac{1}{4}$ of an ounce. The apples 75 are fed to the chute 3 and as they pass down said chute they are picked up one by one by the feeding-wheel 5 and carried into the chute 11. From the chute 11 these drop one at a time into the cup 16. The cams 14 are 80 timed to release the arm 30 each time an apple drops into the cup 16 and when said lever 30 is released, the spring 22 acts to move the cup-arm through the arc of a circle up into the position indicated in dotted lines 85 Fig. 1, and the apple is discharged from the cup in somewhat the manner of a projectile. The apple leaves the cup at an angle of about 45° from the horizontal and by making the cup very light in weight, and by adjusting the strength of the spring 22 so that it will throw the smallest sized apple approximately 206 inches, it will throw the largest sized apple only 48 inches, and the 90 points where the intermediate size of apples 95 drop are approximately spaced about 8 inches apart. In this way, I have made the less than $\frac{1}{4}$ oz. difference in weight separate the apples, for example, 8 inches, so that it is an easy matter to drop them into separate 100 bins. The apples leave the cup at velocities varying according to their weight. By testing cups with the pivoted spring arms of different weights I have determined that the lighter the weight of the cup and arm 105 the greater will be the distance of separation of the points where the different sizes of apples fall, and also that by making the arm of spring steel so that it bends when the apple is being thrown a slight additional 110 amount of separation of the points where the apples fall is obtained. The distance the apple is thrown depends entirely upon its weight and upon the constant strength or reaction of the throwing spring, and does not 115 depend upon the velocity with which the machine is running. By making the helical spring 22 stronger the apples would be thrown farther and the separation would be greater. The apples when thrown in this 120 manner into the bags, drop one at a time into the bags and as these bags are spring-supported and yield readily, the apple is not bruised and each apple rolls out into its bin out of the way of the succeeding apple.

The throwing spring acts with a constant force to move the cup in the arc of a circle, and always imparts to the moving empty cup the same amount of force. When the same cup carries an apple, a part of this 130

force is imparted to the apple and the force with which the cup moves is correspondingly reduced. The larger the apple, the more force is imparted to the apple, with a corresponding reduction in force that is imparted to the cup. For this reason, large apples are thrown with a slightly greater force than small apples. The difference in the forces which are imparted to large and small apples does not equal their difference in weight, and for this reason the small apples are thrown greater distances than the large ones.

When the apple is being thrown the centrifugal force pushes the apple hard against the outer rim of the cup and to prevent its being bruised or checked in its movement by catching under the rim is the purpose of the stiffening plate 19, and furthermore, said plate prevents the leather of the cup from moving in the direction of the apple or passing up through the rim of the cup when the arm is released and the apple discharged.

After the discharge of the apple, the cam 14 again engages the lever-arm 30 and through connections described, the cup is quickly brought back to receiving position to receive the next apple which is brought over from the chute 3 by the feeding wheel 5. The apparatus works with great rapidity and accuracy when once adjusted for a certain variety of apples and the tedious labor of sorting the apples by hand is done away with, while the cost of sorting is greatly reduced, and the only manual labor involved is in packing the apples in boxes.

While I have described my invention and referred to it as adapted for the sorting or sizing of apples, I wish to include within its scope other fruits, as well as nuts and vegetables, or even other articles in the sorting or sizing of which it may be found applicable.

What I claim is:

1. In apparatus, for sizing fruit, the combination with a suitable frame, of a grooved feeding-wheel, pins in said groove, a spring-actuated swinging arm, a cup carried thereby, means for holding said arm in receiving position with reference to said wheel, means for releasing said arm, and a series of receptacles at varying distances from said cup.

2. In apparatus for sizing fruit, the combination with a suitable frame, of a grooved feeding-wheel, pins in said wheel, of a spring actuated swinging-arm, a cup carried thereby, a lever, connections between said lever and said arm, cams at intervals on said feed-

ing-wheel adapted to engage said arm to hold the cup in receiving position with reference to said wheel, and a series of receptacles at varying distances from said cup.

3. In apparatus for sizing fruit, the combination with a suitable frame, of a chute, a feeding-wheel in operative position with reference to said chute, a spring actuated swinging arm, a cup carried by said arm, means for holding said arm with said cup in receiving position with reference to said wheel, means for releasing said arm, and a series of receptacles at varying distances from said cup.

4. In apparatus for sizing fruit, the combination with a suitable frame, of a spring actuated swinging arm, a flexible cup carried thereby, a stiffening member on said arm connected to said cup, and a series of receptacles at varying distances from said arm.

5. In apparatus for sizing fruit, the combination with a suitable frame of means for throwing the fruit, a yieldingly mounted receptacle to receive the fruit having a discharge opening therein, a bin to receive the fruit and a buffer in the path of the fruit in passing from said receptacle to said bin.

6. In apparatus for sizing articles, the combination with a suitable frame of a spring actuated throwing means for throwing the articles different distances according to weight.

7. In apparatus for sizing articles, the combination with a suitable frame, of a swinging arm, a cup carried thereby and a spring connected to said arm.

8. In a device for sizing fruit comprising a sizing distributor, a plurality of receivers and a plurality of bins located on each side of said receivers and communicating therewith, the receivers in succession discharging the fruit to the right and to the left into said bins.

9. In a device for sizing fruit comprising a sizing distributor, a plurality of receivers having oppositely inclined bottoms and a plurality of bins located on each side of said receivers and communicating therewith, said receivers in succession discharging the fruit to the right and to the left into said bins.

In testimony whereof, I the said WILLIAM G. PRICE have hereunto set my hand.

WILLIAM G. PRICE.
